6 Claims. (Cl. 60—64)

This invention relates to steam turbines having a sub-atmospheric pressure stage provided with a low pressure steam sealing gland to reduce to a minimum the leakage of air from the atmosphere to the turbine. Such a low pressure sealing gland generally comprises at least one annular or similar channel provided in the region of the casing of the sub-atmospheric stage which is exposed to the atmosphere and which surrounds the turbine rotor shaft. Sealing steam is supplied to the gland at a pressure and in a quantity sufficient to ensure that the amount of sealing steam discharged through a clearance, at the gland, between the rotor shaft and the casing is adequate to prevent ingress of air through the clearance and into the turbine.

The sealing steam should be at a temperature within the range 220° F.—260° F., at a pressure slightly above atmospheric pressure, and should preferably be slightly superheated to avoid the danger of condensation in the gland and of condensate entering the turbine.

The sealing steam is conveniently derived from a main turbine boiler or from steam discharged from a steam sealing gland in a high pressure stage of the turbine; steam derived from both these sources is however at an excessive temperature and an excessive degree of superheat for direct use in the low pressure gland and must accordingly be desuperheated.

Desuperheating may be effected by means of a heat exchanger disposed within a turbine main condenser. Such an arrangement produces wide variations in the temperature of the sealing steam as a result of variations in turbine loading and/or running conditions. Alternatively desuperheating may be effected by injecting a spray of condensate into the superheated steam flowing to the sealing gland, or by passing the superheated steam into heat exchange relationship with cooling tubes conveying a flow of cooling liquid. In both cases the rate of spray injection or cooling liquid flow, as the case may be, must be automatically controlled in order to maintain the temperature and degree of superheating of the sealing steam reasonably constant. In the event of a fault occurring in the automatic control the temperature and degree of superheat of the sealing steam will violently fluctuate; if the fault, in particular, results in overcooling of the sealing steam, condensation of the steam in the sealing gland may occur and the sudden entry of condensate from the gland into the turbine may have very damaging effects.

An object of the present invention is the provision of an improved steam turbine in which the temperature and the degree of superheat of sealing steam supplied to a low pressure sealing gland are suitably stabilised regardless of turbine loading and without resort to automatic control.

According to the present invention a steam turbine having a sub-atmospheric pressure stage provided with a low pressure steam sealing gland, includes a desuperheater distinct from a turbine main condenser and arranged to bring superheated steam from a suitable source into heat exchange relationship with the condensate of steam discharged from the turbine before the steam enters the sealing gland, when the turbine is in operation.

The invention will now be described by way of example with reference to FIGURES 1 and 1a of the accompanying drawing which schematically shows a suitable desuperheater for supplying sealing steam to a low pressure sealing gland in a steam turbine.

Referring to FIGURE 1 of the drawing the steam turbine includes a sub-atmospheric pressure cylinder 1 provided with a low pressure sealing gland 2 at the region of the cylinder casing 3 which is exposed to the atmosphere and which surrounds one end of the rotor shaft 4. A high pressure sealing gland 14 is provided at the other end of the casing 3.

Pipelines 5 and 6 connected respectively to the inlet and outlet of the gland 2 feed sealing steam to and collect steam discharged, from, the gland 2. Pipelines 15 and 16 respectively feed steam to and collect steam discharged from, the high pressure gland 14. The inlet and outlet of each of the sealing glands 2 and 14 comprises suitable manifolds and are not shown in the drawing.

The pipeline 5 is connected to one end of a heat exchange coil 7 sealed into the lower end of a chamber 8, the other end of the coil 7 being connected to a boiler supplying superheated steam to the turbine and to the high pressure sealing gland 14. The pipeline 6 is connected to the upper end of the chamber which has, also at its upper end, a vent 9 open to atmosphere. In this case when the turbine is in operation the boiling point temperature of the condensate cannot exceed about 212° F.

A heat exchange coil 10 arranged to convey a flow of a suitable cooling liquid is sealed also into the upper end of the chamber 8. The cooling liquid flowing through the coil is in this embodiment feed water for the turbine boiler.

With the turbine in operation steam discharged from the gland 2 enters the chamber 8, through the pipe line 6, is condensed by heat exchange with the coil 10 and falls to the lower end of the chamber 8 where it is permitted to reach a maximum level indicated by the dotted line 11, to completely immerse the heat exchange coil 7. The level of condensate is prevented from rising above the level 11 by an overflow actuating mechanism in the form of a ball valve 12 which operates a drain valve 13; the drain valve can also be used to completely empty the condensate from the chamber 8.

Superheated steam from the turbine boiler passes through the heat exchange coil 7, is desuperheated by heat exchange with the condensate which is kept boiling by the desuperheating heat transfer and passes into the gland 2 through the pipe line 5. The steam released by this boiling action is again condensed by heat exchange with the coil 10.

By the use of the desuperheater arrangement described above, air absorption into the condensate is prevented and corrosion in the steam system of the turbine is correspondingly reduced. Furthermore the temperature of steam discharged from the coil 7 and entering the gland 2 will only slightly exceed and cannot fall below, the boiling point of the condensate at the pressure existing in the chamber 8 and will vary only little irrespective of turbine loading and running conditions, and irrespective of the steam quantity flowing through the heat exchange coil 7.

In an alternative embodiment of the invention as shown in FIGURE 1a the vent 9 at the upper end of the chamber 8 includes, for example, a pressure release valve or a restricted orifice 17 to maintain the pressure in the chamber above atmospheric pressure. In this case the boiling point temperature of the condensate in the chamber 8 is maintained above 212° F. and further reduces the risk of condensation in the gland 2.

In a further embodiment of the invention, the chamber 8 and the heat exchange coils 7 and 10, are replaced by three enclosures defined by three concentric tubes or hollow spheres, the inlet and outlet of each enclosure passing sealingly through any adjacent surrounding enclosure. Alternatively, the second enclosure may be disposed with altogether without interfering with the function of the desuperheater; instead, a suitable relief valve can relieve the steam produced by boiling the condensate into the condenser or a low pressure feed heater, ensuring that the pressure in the first enclosure is always slightly above atmosphere. Such an arrangement, however, may be more prone to instability.

What I claim is:

1. A steam turbine comprising:

- (a) a superheated steam source,
- (b) a sub-atmospheric pressure stage,
- (c) a low pressure steam sealing gland provided in the sub-atmospheric stage and effective to reduce to a minimum ingress of air from the atmosphere and into the stage,
- (d) a desuperheater distinct from a turbine main condenser and comprising heat exchange means, arranged to condense steam discharged from the turbine and desuperheating means arranged to bring superheated steam from the source into heat exchange relationship with the condensate before the steam enters the sealing gland.

2. A steam turbine according to claim 1, wherein the desuperheater comprises:

- (a) a first enclosure having its inlet and outlet connected respectively to a steam discharge point on the turbine and atmosphere,

5
10

15

20

25

30

(b) a second enclosure in heat exchange relationship with the first enclosure and arranged to convey a flow of cooling liquid whereby to effect the condensation of steam passing into the first enclosure, and

(c) a third enclosure arranged to be in heat exchange relationship with the condensate collecting in the first enclosure and having its inlet and outlet connected respectively to the steam source and the inlet of the sealing gland.

3. A steam turbine according to claim 2, wherein the first enclosure is connected directly to atmosphere so that the condensate in the desuperheater is maintained under atmospheric pressure whereby to prevent its boiling point temperature exceeding about 212° F.

4. A steam turbine according to claim 2, wherein the first enclosure is connected indirectly to atmosphere so that the condensate is maintained above atmospheric pressure whereby to permit its boiling point temperature to exceed 212° F.

5. A steam turbine according to claim 1, wherein the condensate is derived from steam discharged from the sealing gland.

6. A steam turbine according to claim 4, wherein the first enclosure has its inlet connected to the outlet of the sealing gland so that the condensate is derived from steam discharged from the sealing gland.
